COMBINATION BURNER

John S. Zink, Tulsa, Okla.

Application October 28, 1936, Serial No. 108,101

7 Claims. (Cl. 158—11)

This invention relates to improvements in burners and more particularly to combination oil and gas burners used in industrial heating furnaces such as are employed in connection with 5 stills, boilers and the like.

A principal object of this invention is to provide a highly efficient combination which permits either the oil or the gas burning portion to be removed from service without disturbing the operation of the other fuel burning portion and without requiring dismantling of the main burner housing or supporting structure and without necessitating alteration or dismantling of auxiliary appliances, such as registers for admission 15 and control of air for combustion.

Another object of this invention is to provide a burner having the above advantages which, at the same time, will be cheaper to construct and simpler to operate than those heretofore known.

Other objects and advantages of my new burner will become apparent from the following description when read in conjunction with the accompanying drawings, which illustrate one of the preferred forms of my burner.

Fig. 1 is a sectional elevation showing the entire burner assembly.

Fig. 2 is an isometric view of the burner assembly, and

Fig. 3 is a detail showing the position of the gas burner as it is withdrawn through the opening provided in the burner supporting plate.

Referring to the drawings, the burner assembly is shown mounted in burner opening 4 in a furnace wall 5. (Fig. 1.) The burner assembly and 35 mounting consist of a flanged ring 6 surrounding the opening 4 and fastened to wall 5 by bolts or other suitable means. A burner supporting plate 7 is supported by ring 6 and spaced therefrom by spacers 8. A hollow tubular member 9

40 extends through a hub or bearing 10 mounted exteriorly of plate 7 and located substantially in the center thereof. Member 9 extends through plate 7, the space between plate 7 and ring 6 and for some distance horizontally into opening

45 4. It is slidable in hub 10 and may be adjusted horizontally to any extent desired. Hub 10 serves to carry member 9 and center it in the burner assembly and opening 4. An oil burner 11 comprising an internal steam supply pipe 12 and an external oil supply pipe 13, connected together at the burner head 14, is inserted through plate 7 and through the member 9 until burner head 14 projects beyond the inner end of member 9. Steam pipe 12 and oil pipe 13 are also 50 joined together outside plate 7 by means of a

bushing 14a to cause steam to travel toward head 14. This is a common type of oil burner in which steam is admitted through pipe 12 and serves to atomize the oil admitted through pipe 13, and to discharge the resulting steam-oil mixture into the furnace through openings 15 in the head 14. A small circular opening 16 is provided in plate 7 in close proximity to hub 10. A gas supply pipe 18, one end of which is connected to one side of a ring shaped gas burner 17, is inserted through opening 16 into the burner housing. Burner 17 is made in the form of a hollow ring having that part of its surface which faces toward the furnace opening 4, pierced with a series of small holes 19 for the discharge of fuel gas 15 from the burner 17 into the furnace. An axial opening 20 is provided in burner 17 of such size as to permit burner 17 to encompass member 9 and to be freely slidable thereon.

In assembling the complete burner, gas burner 20 17, mounted on the end of pipe 18, is inserted through opening 16 in plate 7 in the position shown in dotted outline at the left of Figs. 1 and 3, and is then pushed forward until it extends beyond oil burner head 14 whereupon burner 17 25 is turned until opening 20 registers with the inner end of member 9. Pipe 18 is then drawn backward until it encircles the pipe 9 and oil burner head 14 extends beyond gas burner 17. Pipe 18 is now above and lies parallel to member 30 9 and is supported at the burner end by member 9 and at the other end by the collar 9a which surrounds said member. Pipes 12, 13 and 18 are then connected to their respective sources of supply by means of unions 21, 22 and 23, respectively. 35 Parti-circular doors 24 and 25 are pivotally mounted on the outside of plate 7 on a bolt 26, to cover the opening 16 through which gas burner 17 and pipe 18 extend. Notches 27 and 28 in the lower ends of doors 24 and 25 respectively 40 permit them to close with a relatively tight fit about pipe 18 and thus completely close the opening 16.

In the form of burner illustrated in the drawings, a louvre type air register 29 is used to regulate the volume and direction of the air admitted to the burner opening 4 for regulating the combustion of the fuel used. As illustrated in the drawings, register 29 consists of a solid plate 30 which is slidably mounted on member 9 by means 45 of a centrally located sleeve or hub 31. A series of louvres 32 mounted on the furnace side of plate 30 extend horizontally toward opening 4 and are so placed that air passing into the furnace therethrough, while travelling in a generally 50

horizontal direction, will be given a swirling action as determined by the angle at which the louvres 32 are set against plate 30. This swirling motion of the incoming air combined with the direction of travel of the oil or gas provide effective mixing of the air with the fuel to give most efficient combustion. The direction of travel of the gas or oil is determined by the angle at which the openings or jets 15 and 19 of the oil and gas burners 14 and 17 respectively are set and may be varied by changing burner heads 14 and 17 to meet the desired conditions.

The plate 30 is provided with an opening above the hub 31 to permit insertion and removal of the gas burner 17, and this opening is normally closed by a removable door 40.

In order to regulate the volume of air supplied to the burners through register 29, the register is slidable forward and back on member 9 by means of rods 33, (only one of which is shown,) fastened to plate 30 and extending through suitable openings in plate 7 and terminating in handles 34. By means of the handles and rods, the register 29 may be moved inwardly until the plate 30 entirely closes opening 4 or outwardly until opening 4 is fully open to the surrounding air, or register 29 may be positioned at any point between these extremes to regulate the volume of air entering the furnace through opening 4.

When the described louvre type register is used in my new burner sufficient unobstructed space is provided between the inner edges of louvres 32 and hub 31 to permit burner 17 to pass when being inserted into or removed from the burner housing.

The particular advantages of the new burner appear under the following circumstances: If the gas burner 17 is in use to supply the necessary combustion gases to the furnace and for some reason the burner becomes inoperative, as when jets 19 become clogged, the oil burner 14 may be lighted and put into service and it is only necessary to shut off the supply of gas to pipe 18 and burner 17, break union 23, move pipe 18 and burner 17 toward the furnace until burner 17 clears the tip of burner head 14, then turn pipe 18 until burner 17 assumes an upright position, and then withdraw pipe 18 and burner 17 from the housing through opening 16 in plate 7.

After repairing burner 17, it may be reinserted into the housing and the burner assembly in the manner previously described, and when pipe 18 is reconnected to the source of gas supply by the use of union 23, this burner is ready to go back into service. It will be noted that all of these operations may be conducted without disturbing oil burner 14 and its connecting pipes 12 and 13 and without disturbing the air register 29 although it may be necessary to change its position to provide a different quantity of air for the other fuel, in producing efficient combustion of that fuel. Similarly, if the oil burner 14 becomes inoperative it is only necessary to disconnect unions 21 and 22 and withdraw this portion of the combination burner from the housing by withdrawing pipes 12 and 13 and head 14 from the interior of member 9, this time without disturbance of gas burner 17 or the air register 29. In this case, of course, gas burner 17 will remain in service in the furnace while the oil burner is being repaired.

It will be understood that the new burner will be advantageous where no air register is used and where ring 6 and plate 7 are formed as a unit bringing plate 7 against the wall 5 of the

furnace, but, of course, some other means of providing air for combustion must be supplied. Also the space between plate 7 and ring 6 may be entirely enclosed with a hood and air for combustion may be introduced by forced draft, and in this case register 29 may or may not be required.

The sizes of burners 14 and 17 may vary in accordance with the capacity required by the service for which the burners are to be used. In every case the interior diameter of member 9 and the diameter of opening 16 will be adequate to permit assembly or taking apart of the respective burners in the manner described. However, the burner 17 is always sufficiently small so that opening 16 will be relatively small in diameter as compared with the diameter of plate 7.

Burners 14 and 17 are generally made of heat resisting metal and are readily removable from the ends of their respective pipes for cleaning or for replacement.

As burner 14 and its connecting pipes 12 and 13 are slidably mounted in member 9, and burner 17 and pipe 18 are likewise slidably mounted in opening 16 and on member 9, both burners are adjustable horizontally to any desired extent with respect to the furnace opening and to the front edges of louvres 32 and are also adjustable relative to each other.

By designing gas burner 17 in the form of a ring encompassing oil burner 14 and with circular rows of gas jets 19 in the surface of the ring, the fuel gas is discharged uniformly and produces a uniform mixture with the entering combustion air thus providing highly efficient combustion of the gas. Similarly, by locating oil burner 14 in the center of the combination assembly and by suitable arrangement of jets 15, a similar even distribution of oil fuel in the combustion air is produced and efficient combustion results.

Although I have described a specific embodiment of my invention, as applied to combination burners, it will be obvious to those skilled in the art that various modifications may be made in the details of construction and in the arrangement of the several cooperating parts without departing from the principles herein set forth.

What I claim and desire to secure by Letters Patent is:

1. An oil and gas burning apparatus including a supporting plate, said plate having two adjacent ports, one of said ports being substantially in the center of said plate, an oil burner mounted in said centrally located port, a gas burner mounted in the other port, said gas burner including a ring shaped burner head encompassing said oil burner, and each of said burners being independently removable from the combination without disturbance of the remaining burner.

2. An oil and gas burning apparatus comprising a plate having a bearing, a conduit slidably mounted in said bearing, an oil conducting pipe extending through the conduit, an oil burner nozzle arranged at one end of said pipe, the plate being provided with an opening adjacent to the bearing, a gas conveying pipe extending through the opening in the plate and parallel to said conduit, an annular gas burner surrounding said conduit and connected near its peripheral portion to the discharge end of the gas conveying pipe, the opening in the plate being of sufficient size to permit the gas burner and the gas conveying pipe to pass therethrough, and a door on

the plate closing said opening when the gas pipe extends therethrough.

3. An oil and gas burning apparatus comprising a vertically disposed plate having a bearing, a horizontal conduit extending through the plate and slidably mounted in said bearing, oil and steam conducting pipes extending through the conduit, an oil burner arranged at one end of said pipes and operatively connected to the same, 5 said plate being provided with an opening adjacent to said bearing, a gas conveying pipe extending through the opening in the plate, an annular gas burner surrounding said conduit and connected to one end of the gas conveying 10 pipe, the opening in the plate being of sufficient size to permit the gas burner and gas conveying pipe to pass therethrough, the oil burner and the gas burner being removable from the conduit and plate independently of one another, and means 15 for closing the opening in the plate while the gas conveying pipe extends therethrough.
4. An oil and gas burning apparatus comprising a plate having a bearing, a substantially horizontally disposed conduit extending through the plate and mounted in said bearing, an oil conducting pipe and a steam conducting pipe extending through said conduit, an oil burner operatively connected to end portions of said pipes, 20 said plate being provided with an opening adjacent to said bearing, a gas conveying pipe extending through said opening and terminating adjacent to said oil burner, and an annular gas burner surrounding said conduit and having a peripheral portion, one end of the gas conveying pipe being 25 connected to the gas burner near the peripheral portion of the latter, the opening in the plate being of sufficient size to permit the gas burner and the gas conveying pipe to be inserted or removed while said conduit and the oil burner remain in normal position, and said oil pipe, steam 30 pipe and oil burner being also insertable into or removable from the conduit while the gas burner remains in normal position.

5. In combination, a furnace wall having an opening therein, an oil and gas burning apparatus comprising a plate, means for supporting said plate opposite the opening in said furnace wall, a tubular member extending through said plate into 35 said opening, and an oil burner mounted in said

tubular member and projecting beyond the latter into said opening, said plate being provided with a port adjacent said tubular member, a gas supply pipe extending through said port toward said opening, and a substantially ring-shaped gas burner attached to the inner end of said pipe, 5 said gas burner having an axial opening of a size to permit said gas burner to be slipped over said oil burner and said tubular member.

6. A combination oil and gas burner comprising 10 supporting means, an oil conveying conduit supported by said means, an oil burner nozzle connected to the discharge end of said oil conveying conduit, a gas burner nozzle through which the oil conveying conduit extends, said nozzles being 15 arranged in close proximity to one another with the oil burner nozzle normally projecting beyond the gas burner nozzle, gas conveying conduit means connected to said gas burner nozzle for furnishing gaseous fuel to the latter, said gas 20 burner nozzle and the gas conveying conduit means being supported by the supporting means and being removable from the latter while the oil burner is in operation without disturbing the latter, and said oil burner nozzle and oil 25 conduit being removable from said supporting means while the gas burner is in operation without disturbing the latter.

7. A combination oil and gas burner comprising 30 supporting means, an oil conveying conduit supported by said means, an oil burner nozzle connected to the discharge end of said oil conveying conduit, a gas burner nozzle through which the oil conveying conduit extends, said nozzles being 35 arranged in close proximity to one another with the oil burner nozzle normally projecting beyond the gas burner nozzle, gas conveying conduit means connected to said gas burner nozzle for furnishing gaseous fuel to the latter, said gas burner nozzle and the gas conveying conduit 40 means being supported by the supporting means and being removable from the latter while the oil burner is in operation without disturbing the latter, and said oil conveying conduit and oil 45 burner nozzle being detachably connected to the supporting means and being removable from the latter while the gas burner is in operation without disturbing the gas burner.

JOHN S. ZINK.
